CLAIM

[21] Appl. No.: 551,201

The ornamental design for a vane holder for vertical blinds, as shown and described.

[22] Filed: Nov. 14, 1983

DESCRIPTION

[52] U.S. Cl. D6/580; D6/575;

FIG. 1 is a perspective view of a vane holder for vertical blinds showing my new design, the vane shown separately in broken lines for illustrative purposes only; FIG. 2 is a front elevational view thereof; FIG. 3 is a rear elevational view thereof; and, FIG. 4 is a bottom plan view thereof.
